ALEXANDER T. KOPPE, OF CHICAGO, ILLINOIS, ASSIGNOR TO DIRECTOPLATE CORPORATION, OF CHICAGO, ILLINOIS, A CORPORATION OF ILLINOIS.

PROOF PRESS.

Application filed December 20, 1924. Serial No. 757,104.

This invention relates to improvements in proof presses adapted for use in proving lithographic work from zinc or aluminum plates or other sensitized sheets used in offset printing and for other like purposes. In the practice of offset printing, before the sensitized sheet of relatively large size bearing a complete series of impressions of the object to be reproduced is employed in the usual 5 press for reproducing the object or design in a commercial printing operation, it is desirable to go through a preliminary proving operation in which a plate of zinc or the like, bearing lithographic design which has been 10 transferred thereto by photographic or other means, is placed in a proof press in which the impression on the inked zinc plate is first transferred to a transfer cylinder and then impressed by this cylinder on a sheet of paper, 15 successive operations of the proof press being performed to reproduce one or all of the colors of the design or object on the sheet of proof paper. Since sensitized plates, 20 such as those of zinc and the like, and the sheets of proof paper may vary considerably 25 in thickness from time to time and between successive operations of the proof press, it is desirable to provide means for compensating for this variation in thickness 30 so that the transfer cylinder will bear with substantially the same pressure on the zinc plates and the sheets of paper at all times. It is therefore an important object of the present invention to provide an 35 improved proof press comprising improved means for effecting relative adjustment of the bed-plates, upon which the zinc sheets and paper sheets are mounted, with respect to the transfer cylinder. Still another object is to 40 provide improved adjusting mechanism whereby either of the bed-plates upon which the zinc plates and paper sheets are mounted may be adjusted vertically while maintaining 45 their upper surfaces at all times parallel to the surface of the transfer cylinder. Still another object is to provide means for effecting independent adjustment of different parts 50 of each bed-plate so that the upper surface of the bed-plate may be adjusted into the desired plane. Another object of the invention is to provide means for securing identity of registration of the transfer cylinder with the bed-plate bearing the paper sheet and the bed-plate bearing the zinc plate, in successive 55 operations, so that different colors may be re- produced in the object or design being proved without overlapping of the different colors or designs. A further important object of the invention is to provide improved means for securing the paper sheets on the bed-plate 60 and for properly positioning the paper sheets thereon. Still another object is to provide improved means for moving the transfer cylinder to and from the plane of the upper surfaces of the bed-plates. A further feature 65 of the invention is the provision of means for moving the bed-plate beneath the transfer cylinder and for controlling the starting and stopping of this actuating mechanism. Another object is to provide means for automatically 70 elevating the transfer roll at the end of travel of the bed-plate. A further feature is the provision of improved means for supporting the bed-plates during their travel. A further object of the invention is to provide 75 improved means for securing the rubber blanket or other transfer member in position on the cylinder. Other objects relate to various features of construction and arrangement which will appear more clearly herein- 80 after.

The nature of the invention will be understood from the following specification taken with the accompanying drawings in which one embodiment is illustrated. In the drawings, Figure 1 shows a side elevation of the improved proof press; Fig. 2 shows a partial side elevation of the machine, illustrating the positions of the parts of the actuating mechanism of the transfer cylinder when the 85 cylinder has been raised; Fig. 2^a is a vertical section taken inside the side frame showing the mechanism for operating the gripper shaft; Fig. 3 shows a top plan view of the proof press; Fig. 4 shows an end elevation of 90 the machine, looking toward the right as viewed in Fig. 1; Fig. 5 is a detail section taken on the line 5—5 of Fig. 4; Fig. 6 shows a longitudinal section taken on the line 6—6 95 of Fig. 3; Fig. 7 shows a longitudinal section taken on the line 7—7 of Fig. 3, the views of Figs. 6 and 7 showing a complete longitudinal section through the machine with the carriage displaced on the opposite side of the transfer roll from that shown in Fig. 3; Fig. 100 8 is a detail section taken on the line 8—8 of Fig. 7; Fig. 9 shows a transverse section taken on the line 9—9 of Fig. 3; Fig. 10 shows a top plan view of the machine with the bed-plates 105 removed and with parts thereof broken away; Fig. 110

Fig. 11 shows a plan view of the transfer cylinder, illustrating the improved means for securing the rubber transfer blanket thereto; Fig. 12 shows a partial enlarged transverse section taken on the line 12—12 of Fig. 11; Fig. 13 shows a transverse section through the transfer cylinder taken on the line 13—13 of Fig. 11; Fig. 14 shows a partial longitudinal section through the transfer cylinder taken on the line 14—14 of Fig. 11; Fig. 15 is a longitudinal detail sectional view taken on the line 15—15 of Fig. 3, showing the transverse register slide of the bed-plate for the paper and the means for holding the paper sheet in position thereon; Fig. 16 shows a detail section taken transversely of the machine through the register slide on the line 16—16 of Fig. 15; Fig. 17 shows a section taken longitudinally of the machine on the line 17—17 of Fig. 3, showing the means for positioning the paper sheet longitudinally of the bed-plate; Fig. 18 shows a perspective view of an auxiliary rack bar section which is employed for securing exact registration of the transfer cylinder and the bed-plates in successive operations of the machine; Fig. 19 is a perspective view of a complementary rack bar section which is employed in connection with that illustrated in Fig. 18; Fig. 20 shows an enlarged end elevation of a portion of the transfer cylinder and the gear which rotates therewith, illustrating the engagement of the teeth of this gear with the main rack bar and with the auxiliary rack bars shown in Figs. 18 and 19; Fig. 21 shows a top plan view of the main rack bar having mounted therein the auxiliary rack bars shown in Figs. 18 and 19; Fig. 22 shows a top plan view of the motor controller by which the direction of rotation of the motor is automatically reversed at the ends of travel of the bed-plates; Fig. 23 is a vertical section taken on the line 23—23 of Fig. 6 through the friction brake for controlling the rotation of the screw shaft; Fig. 24 shows a side elevation of the controller mechanism illustrated in Fig. 22; Fig. 25 shows a side elevation of the controller mechanism, looking toward the opposite side from that illustrated in Fig. 24; and Fig. 26 is a diagrammatic view showing the electrical connections of the reversing controller and other devices for controlling the operation of the driving motor.

As illustrated in the drawings, the invention comprises a supporting frame 30, comprising a pair of side frames or standards 31, each having a part 31^a extending upwardly from a floor or other support, and provided with longitudinal extensions 31^b extending in opposite directions thereon. The side frames 31 are united by a pair of transverse frame members 32, having the form illustrated particularly in Figs. 4, and 6, where each transverse frame is shown as comprising an upwardly extending part 32^a and a horizontally

projecting shelf portion 32^b, these transverse frames being provided at their ends with laterally projecting flanges 32^c which are secured to the side frames 31 by means of bolts 33. The parts 32^b are formed integrally with or connected to two other transverse frame members 34 having flanges 34^a at their ends which are connected to the side frames by bolts 35, these transverse frame members 34 supporting the bearings 36 of the longitudinal power-driven screw shaft 37 by which the bed-plates are moved longitudinally of the machine. The threaded portion of the screw shaft 37 threadedly engages an internally threaded sleeve or nut 38 which is secured to the underside of a carriage 40, as shown in Fig. 7 so that the rotation of the shaft moves the carriage with respect to the frame 30. The carriage 40 supports the bed-plates 41 and 42 which are adapted to carry the lithographed plates and the paper sheets, respectively, and to travel beneath the transfer cylinder 44 which is provided with trunnions 45 journaled in bearings carried by the bearing brackets 46 secured to the side frame members 31. In the operation of the machine, a plate bearing a lithographed design is placed on the bed-plate 41 and as the carriage 40 moves longitudinally of the machine, the design to be reproduced is transferred to the cylinder 44 by which it is in turn transferred to the paper sheet mounted on the bed-plate 42 as the longitudinal movement of the carriage 40 continues.

The carriage 40 is in the form of a rectangular frame of box-like form having a central transverse member 40^a, side members 40^b, and transverse end members 40^c and 40^d. The side members 40^b of the carriage 40 travel on two series of cylindrical rollers 50 which roll on trackways 51 formed integrally with the side frame members 31, as shown particularly in Fig. 9. The rollers 50 are mounted on spindles 52 which extend outwardly from roller bars 53. The trackways 51 are grooved slightly as shown at 51^a to receive the rollers 50 and the roller bars 53 adapted to travel above the shoulders 54 which are formed at the inner sides of the grooves. The rollers 50 are preferably so designed that the roller bars 53 travel longitudinally of the frame 30 with a speed substantially half of the longitudinal speed of the carriage 40, and this arrangement substantially eliminates friction between the rollers and the contacting surfaces of the frame and carriage. The roller bars 53 are adapted to slide in guideways 55 which are formed in the underside of the side members 40^b of the carriage and the bars are retained in these guideways by the detachable bars 56 which are secured to the under side of the carriage by cap screws or the like. In order to retain the bars 53 and their rollers in the same relative positions at all times with respect to the carriage 40, in any

given position of the carriage 40 each bar 43 is provided with an inwardly projecting spindle 58 having mounted thereon a pinion 60 adapted to mesh with a rack bar 61 secured to the side frame member 31 and with another rack bar 62 secured to the bar 56 carried by the carriage 40. As the carriage 40 moves longitudinally of the frame 30, the weight of the carriage is supported by the rollers 50 and the pinions 60 meshing with the rack bars 61 and 62 at the sides of the machine serve merely to maintain the roller bars 53 in the proper relative positions with respect to the carriage. The sides of the carriage are spaced inwardly somewhat from the side walls of the frame 30, as shown in Fig. 4, and the carriage is maintained in position laterally of the frame by means of rollers 65 which are adapted to contact with the vertical surfaces of trackways 66 formed on the side walls of the frame. At one side of the machine the rollers 65 are mounted on pivots carried by brackets 67 which are secured in fixed position on the ends of the carriage 40, as shown in Fig. 4, but at the other side of the machine, the rollers 65 are mounted on pivots carried by brackets 68 which are slidably mounted on the ends of the carriage 40, these brackets 68 being forced normally in an outward direction by means of coil springs 69 which are mounted between lugs 70 on the carriage and the flanges 71 of the bracket so that the adjacent rollers are maintained in contact with the adjacent trackway 66 and lateral movement of the carriage is at all times prevented. As shown in Fig. 5, the brackets 68 are slidably mounted in guides 72 fixed on the carriage 40.

The bed-plate 41 is supported by two shafts 75 journaled in eccentrics 76 which, in turn, are journaled in the side members 40^b of the carriage and maintained in position by collars 76^a fixed on the shafts 75. One of the transverse ribs 41^a on the under side of the bed-plate 41 rests on each of the shafts 75 and the longitudinal ribs 41^b are hollowed out as shown at 77 to receive the shafts 75. Longitudinal movement of the bed-plate 41 in one direction within the carriage is prevented by means of stop screws 78 which threadedly engage the end wall 40^d of the carriage and are held in adjusted position by means of wing nuts 79. The zinc plate 80 rests on the upper surface of the bed-plate 41 and the end thereof toward the right-hand end of the machine, as viewed in Fig. 6, is secured in place on the bed-plate by means of channel-shaped bars 82 which are adjustably attached to the bed-plate by means of cap screws 83. The corner of the bed-plate is beveled as shown at 84 and the upper flange of the bar 82 contacts with the zinc plate 80 opposite this beveled surface so that the upper edge of the bar 82 is displaced downwardly from the upper surface of the zinc plate.

In the operation of the machine, the carriage 40 and the bed-plate 41 travel toward the right as viewed in Fig. 6, as indicated by the arrow 84, when the zinc plate is engaged by the transfer cylinder, so that it is necessary to attach the zinc plate 80 to the bed-plate only at the leading edge thereof. The bed-plate 42, on which the paper sheet is mounted, is supported on a pair of shafts 85 journaled in eccentrics 86 which in turn are journaled in the side members 40^b of the carriage and maintained in position by collars 86^a fixed on the shafts. One of the transverse ribs 42^a of bed plate 42 rests on each of the shafts 85 and the longitudinal ribs 42^b thereof are notched out as shown at 87 to receive the shafts 85. The movement of the bed-plate 42 toward the adjacent end of the carriage is prevented by stop members 88 which threadedly engage the end wall 40^d of the carriage and are held in adjusted positions by means of wing nuts 89.

The mechanism for adjusting the bed-plate 41 in a vertical direction is the same as the mechanism for adjusting the bed-plate 42 in a vertical direction and a description of one of these mechanisms will therefore suffice for both. Each of the eccentrics 76 and 86 has formed integrally therewith or rigidly connected thereto an eccentric arm 90 and the eccentric arms for each bed-plate are connected longitudinally at each side of the bed-plate by a rod 91 having threaded ends which engage blocks 92 secured in adjusted position longitudinally of the rod by means of lock nuts 93. Each block 92 has a bearing pin 94 projecting laterally therefrom and passing through an aperture in the adjacent eccentric arm 90, these parts being secured in the proper relative positions by means of nuts 95, as shown particularly in Fig. 8. This connection between the rod 91 and the eccentric arms 90 permits any eccentric arm to be adjusted in its angular position independently of any other, so that any corner or section of the connected bed-plate may be raised or lowered independently of other parts of the bed-plate through the operation of the eccentrics 76 or 86, in order that the upper surface of the bed-plate may be located in a horizontal plane parallel to the surface of the cylinder 44. In order to effect the simultaneous elevation of all parts of each bed-plate in equal degree, the rods 91 at opposite sides of each bed-plate are connected to a common actuating member. Referring to Fig. 10, the rods 91 for the bed-plate 41 engage brackets 97 to which they are secured by nuts 98 and these brackets are mounted on a transverse shaft 99 connected to a sliding frame 100 through crank arms 101 having connection with the sliding frame through pins 102. The sliding frame 100 has a longitudinal extension 100^a which is slidably mounted in guideways 103 formed between the base portion 40^e of the carriage and

the guide plates 104 which are detachably secured thereto. The sliding frame 100 is adjusted longitudinally to effect an angular movement of the crank arms 90 through the operation of a hand wheel 105 having a handle 105^a, which is secured on an adjusting screw 106 having a threaded engagement with the barrel 107 which is formed integrally with the sliding frame 100. The adjusting screw 106 extends through a bearing 108 which is carried by the end member 40^a of the carriage and the dial 110 formed on the hand wheel 105 is provided with graduations 111, distributed around it 90 degrees apart, so that the operator may predetermine the extent of vertical adjustment of the bed-plate 41 by the position of the graduations on the dial 110. For example, it may be predetermined that the movement of the dial 110 through 90 degrees will effect a vertical elevation or depression of the bedplate 41 a distance of 3/1000th of an inch and, having previously determined the extent of adjustment necessary, through measurement of the thickness 25 of the zinc plate 80, the operator may effect a precise adjustment of the bedplate through the operation of the hand wheel 105. At the other end of the carriage, the rods 91 which actuate the bedplate 42 are connected to similar mechanism comprising a sliding frame 115 mounted to slide in guideways 116, formed in the base portion 40^a of the carriage in conjunction with the detachable bars 117, and the sliding frame 115 is operated by an adjusting 30 screw 118 having secured thereon a hand wheel 120 having a handle 120^a. The hand wheel 120 carries a dial 121 having graduations 122 marked thereon and distributed 90 degrees apart like the graduations on the dial 110, so that the degree of elevation or depression of the bedplate 42 may be predetermined through knowledge of the extent of movement 40 of the bedplate which is effected by a 90 degree turn of the adjusting screw 118.

45 The paper sheet 125 is held on the bedplate 42 at the leading edge of the bedplate by means of a plurality of gripper fingers 126 which are secured on a shaft 127 journaled in bearings 128 carried by the central part 40^a of the carriage 40. The connection of the gripper fingers 126 with the shaft 127 is made by a key 129 engaging a composite keyway 130 formed in the shaft and in each of the members 126, as shown in Fig. 15, the keyway being 50 slightly larger than the key so that some relative movement of each finger 126 and the shaft is permitted, in order that all of the fingers 126, without being normally in exact alignment, may be brought into engagement with 55 the paper sheet on the bedplate through the operation of a plurality of coil springs 131, each of which is connected at one end to the underside of one of the fingers and at the other end to a pin 133 extending outwardly from 60 one of the transverse ribs 42^a of the bed-plate.

The springs 131 hold the members 126 normally in engagement with the upper surface of the edge of the paper sheet and when it is desired to release the paper from the gripping members and remove it from the bed-plate, the fingers 126 are moved upwardly against the tension of the springs by rocking the shaft 127. For this purpose, the shaft 127 has a crank arm 135 fixed on the projecting end thereof and adapted to be engaged by either 75 one of two other crank arms 136 which are fixed on a shaft 137 journaled in bearings carried by one of the side frames 31, as shown in Fig. 1. Two of the shafts 137 and two of the crank arms 136 are provided so that 80 the shaft 126 may be rocked to release the paper from the bed-plate at either end of the path of travel of the bed-plate. Each shaft 137 has a crank arm 138 connected thereto and arranged to be operated by a rod 139 having its lower end connected to a pedal 140 pivoted on the side of the frame as shown at 141. A coil spring 142 is mounted on each rod 139 between the link 139^a on the end of the rod and a lug 143 which projects outwardly from 90 the side frame, these springs serving normally to hold the crank arms 136 in horizontal positions, as shown in Fig. 4, so that they do not engage the crank arms 135 mounted on the end of the shaft 127. After 95 one of the pedals 140 has been operated to raise the paper holding fingers 126 out of engagement with the paper on the bed-plate 42, the foot pedal is released, and the spring 142 immediately returns the crank arm 136 to its 100 normal position, thereby permitting the holding fingers 126 to return to their normal positions under the influence of the springs 121. The shaft 127 which operates the mechanism for holding the paper sheet on the bed-plate 42 also operates certain devices for positioning the sheet of paper longitudinally on the bed-plate. For this purpose, the shaft 127 is 105 provided with a plurality of positioning members 145 which are constructed in the form of 110 brackets pivotally mounted on the shaft between adjacent gripping members 126 so that the gripping members and the positioning members alternate with each other along the shaft. Each positioning member 145 is provided with a shoulder 146 having slidably 115 mounted thereon a block 147 provided with a stem 147^a which slidably engages an aperture or bore extending through the positioning member as shown at 148. Each member 145 is provided with a slot 149 intersecting the bore 148 and this slot has mounted therein a knurled adjusting member 150 which threadedly engages the stem 147^a so that the position 120 of the block 147 may be regulated as desired. The stems 147^a are held in adjusted position by means of set screws 147^b. Each block 147 carries a pivot pin 151 which engages an angular contact plate 152 having a flange extending 125 downwardly toward the bed-plate and adapt- 130

ed to contact with the edge of the paper sheet when it is positioned on the bed-plate. The positioning members 145 are held in such position that the flanges of the contact members 152 engage the bed-plate through the operation of coil springs 154 which are connected at one end to the positioning members and at the other end to pins 155 which extend outwardly from the flanges 42^a of the bed-plate, 5 as shown in Fig. 15. The pivotal incorrect mounting of the contact pieces 152 permits them to be adjusted in position so that the contacting faces 152^a thereof lie in the desired plane to contact with the edge of the paper sheet. The pivotal mounting of the positioning members permits them to remain in contact with the bed-plate when the grippers 136 are elevated.

The bedplate 42 also carries means for 20 positioning the paper sheet transversely of the bedplate, this mechanism being shown in detail in Figs. 15 and 16. The bedplate 42 is provided adjacent the shaft 127 with a transverse rectangular groove 157 having slidably 25 mounted therein a register slide 158 provided with a plurality of threaded apertures 159 extending downwardly from its top surface so that any one of these apertures may be engaged by a threaded screw 160 engaging a 30 side contact plate 161, having a flat edge face 161^a adapted to contact with the lateral edge of the paper sheet. By causing the screw 160 to engage any desired one of the threaded apertures 159, a considerable variation may 35 be secured in the lateral position of the contact piece 161. A finer adjustment of the position of the contact piece 161 may be obtained through the operation of an adjusting screw 163 which threadedly engages a 40 bore 164 formed in the register slide and which threadedly engages a plate 165 secured to the side of the bedplate. A collar 166 is fixed on the adjusting screw 163 at one side of the plate 165 and the operating member 167, 45 having a dial 168, is secured on the end of the adjusting member at the other side of the plate 165. The dial 168 is provided with graduations so that the extent of movement of the register slide may be predetermined.

The bore 164 in the register slide is provided 50 with an enlargement 164^a having mounted therein a non-circular nut or block 169 which is threadedly engaged by the adjusting screw, and a coil spring 170 is mounted between this 55 block and the shoulder at the end of the part 164^a of the bore so that a tight engagement is maintained at all times between the threads of the adjusting screw and the threads of the slide and slight variations in the position of 60 the register slide are prevented.

The transfer cylinder 44 comprises a flexible pad or blanket 175, of rubber or the like, by which the design or impression to be reproduced is transferred from the lithographed plate 80 to the paper sheet 125. This

rubber blanket is mounted on the outer surface of the longitudinally slotted hollow cylinder 176, forming a part of the transfer cylinder, and one edge of the blanket is secured between a pair of holding bars 177 and 70 178 which are secured together by screws 179 so that they grip the edge of the blanket between them. One of the bars 178 is preferably hollowed out as shown at 178^a so that the edge of the bar more effectually grips the 75 blanket and one edge of the other bar 177 is adapted to extend beneath a shoulder 179 on the inward projection 180 of the cylinder wall so that the holding bars are held in place when tension is produced in the blanket. The 80 other edge of the blanket 175 is secured between a pair of similar gripping bars 181 and 182, secured together by screws and mounted in a longitudinal pocket which is formed in a 85 rotatable cylinder or roll 183 provided at one end with a ratchet wheel 184. The ends of the roll 183 are provided with trunnions 185 which are journaled in suitable bearings 186 carried at the end of the transfer cylinder 44, as shown in Fig. 11, and the roll is rotated to 90 adjust the tension of the rubber blanket 175 by the engagement of a wrench with the squared portion 187 of one of the trunnions 185 at the end of the roll opposite the ratchet wheel 184. The ratchet wheel is held in its 95 adjusted position by means of a detent 189 engaged by a coil spring 190 mounted on a pin 191 carried by the inwardly projecting part 180 of the cylinder so that the spring normally forces the detent into engagement 100 with the ratchet wheel. To permit the operator to disengage the detent from the ratchet wheel when in a position adjacent the other end of the roll 183 where the wrench engageable portion 187 of the trunnion is located, 105 the detent 189 is provided with an arm 192 arranged to overlie an operating bar 193 slidably mounted on the part 180 of the cylinder and held in position by a plurality of cap screws 194 which pass through elongated 110 slots 195 formed in the bar, as shown in Fig. 9. These slots permit the bar 193 to be moved longitudinally toward the inclined end face 196 thereof beneath the operating arm 192 of the detent, as indicated in Fig. 14, thereby 115 forcing the detent out of engagement with the ratchet wheel and permitting the operator to rotate the roll 183 to release the blanket. The bar 193 is provided with an operating handle 197 for engagement by the operator 120 and the bar is normally held out of engagement with the operating member 192 by a leaf spring 199 secured on a block 200 carried by the part 180 of the cylinder, as shown in Fig. 14. This leaf spring is provided with 125 a tooth 199^a adapted to engage a recess 193^a formed in the slidable bar and the bar can be moved longitudinally to disengage the detent only after lifting the leaf spring 199.

The trunnions 45 which carry the trans-

fer cylinder 44 are mounted to rotate in bushings 205 located in eccentric sleeves 206 which in turn are journaled in the bearing brackets 46, previously referred to. The ends of the trunnions 45 are engaged by washers 207 and nuts 208 and the eccentrics 206 are provided with integral crank arms 209 pivotally connected at their outer ends to blocks 210 which are threadedly engaged by operating rods 211 secured in adjusted position in the blocks 210 by means of lock nuts 212. The rods 211 are pivotally connected at their lower ends to crank arms 213 which are fixed on a transverse shaft 214 journaled in the side frames 31. At the front side of the machine, as viewed in Fig. 1, the crank arm 213 is connected to the rod 211 by means of a pivot pin 215 which projects outwardly to be engaged by slot 216 in an operating lever 217 rotatably mounted on the end of the shaft 214. When the lever 217 is moved toward the right as viewed in Fig. 1, to the position shown by dotted lines in Fig. 2, the crank arms operate the rods 211 to rotate the eccentrics 206 and thereby permit the cylinder 44 to be elevated free of engagement with either the lithographed plate on the bedplate 41 or the paper sheet on the bedplate 42. The reverse motion of the eccentrics with a resulting lowering of the transfer cylinder 44, so that the rubber sheet thereof engages with the upper surfaces of the lithographed plate 80 or the paper sheet 125, may be effected manually through the operation of a link 219 which is connected to the pivot pin 215 and arranged to extend longitudinally therefrom. This link has a slot 220 in the end thereof which is engaged by a pin 221 on an operating lever 222 and this operating lever may be moved toward the left, as viewed in Figs. 1 and 2, to effect the lowering of the cylinder towards the bedplate. The movement of the lever 222 toward the right as viewed in Figs. 1 and 2 is limited by means of a stop screw 223 threadedly engaging a lug 224 extending outwardly from the adjacent side frames 31 and this stop screw of course limits also the extent of movement of the link 219 and the crank arms 213 when actuated by the lever 217, so that it determines the extent to which the roll 44 is elevated away from the path of movement of the bedplates. In a similar manner, the lever 217 is limited in its counter-clockwise movement by a stop screw 225 which threadedly engages a lug 226 extending outwardly from the side frames 31, so that the lowering of the cylinder 44 is limited by the engagement of the pin 215 with slot 216 and the engagement of the lever 217 with the stop screw 225. By adjusting the stop screws 223 and 225, any desired range of movement of the transfer cylinder 44 may be obtained. Further adjustment may be secured by regulating the lock nuts 212 in order to vary the positions of the rods 211 in the

blocks 210, whereby varying the normal positions of the eccentrics 206 in their bearings. When the carriage 40 reaches the end of its path of travel toward the right, as viewed in Fig. 7, the cylinder 44 is elevated automatically by the action of an arm 227 fixed on the shaft 214 in the path of movement of a stop member 228 carried by a bracket 229 secured to the end of the carriage 40. The cylinder 44 is provided at opposite ends 75 with bearers in the form of bearing discs or wheels 230 and when the cylinder 44 is lowered by the operation of the eccentric mechanism heretofore described, these bearing members 230 rest on the horizontal bearing surfaces 231 which are formed on the side members 40^b of the carriage 40. When the carriage 40 is moved longitudinally by the rotation of the screw shafts 37, contact between the surfaces 231 and the peripheral surfaces of the drums 230 serves to rotate the transfer cylinder 44 so that the impression on the lithographed plate 80 is first transferred to the rubber sheet 175 and then transferred by the rubber sheet to the paper sheet 125 mounted 80 on the bed plate 42. In the process of providing a particular design or impression which is to be reproduced in the offset printing process, it may be necessary to run through the proof press a plurality of separate lithographed plates in order to reproduce all of the different colors which make up the composite design or impression, and since it is necessary that the various colors be in exact 85 register on the printed sheet, it is important 100 that the part of the rubber sheet 175 on the transfer cylinder 44 which first contacts with the lithographed plate or the paper sheet be brought into engagement with the lithographed plate or the paper sheet in the same 105 relative positions in successive operations of transferring different parts of the composite design from the lithographed plate to the paper sheet through the transfer cylinder. For the purpose of securing this exact registration of the transfer cylinder 44 with the bedplates when the rotation of the cylinder first begins, the cylinder 44 is provided at one end with a relatively fixed gear 233 which is adapted to mesh with a rack bar 234 mounted 110 in fixed position on the carriage 40 at one side of one of the bearing surfaces 231, as shown particularly in Fig. 4. The gear 233 is provided with relatively large teeth 233^a which are adapted to mesh with undercut 115 teeth 234^a formed on the rack bar 234, but at certain points along the rack bar 234, the teeth 234^a are supplemented by teeth of different formations formed on two auxiliary rack bars 235 and 236, having the form illustrated 120 particularly in Figs. 18, 19, 20 and 21. The rack bars 235 and 236 are mounted in rectangular slots 237 which extend inwardly 125 from the outer side of the rack bar 234 and they are held in position by cap screws 238 130

which engage apertures or slots 239 and 240 formed in the rack bars 235 and 236, respectively, and which engage threaded apertures in the rack bar 234. The slots 239 in the rack bar 235 are elongated and the end of this rack bar is provided with a threaded aperture 241 which is engaged by a set screw 242 which may be adjusted to move this rack bar longitudinally for the purpose of varying the position of its teeth with respect to the teeth on the rack bars 234 and 236. The rack bar 235 occupies the inner position in each of the slots 237 and the teeth on each of the auxiliary rack bars 235 and 236 are undercut so that they are relatively small as compared with the teeth 233^a on the gear.

As shown in Figs. 20 and 21, the auxiliary register rack segments 236 and 237 are adjusted longitudinally of the rack bar 234, that they mesh closely with the teeth 233^a of the gear, thereby registering the rack bar with the transfer cylinder 44 with respect to the carriage and the bedplate and locating the teeth 233^a in a clearance position with respect to the teeth of the rack bar 234. When this adjustment is made, the teeth of the auxiliary register rack bars 235 and 236 project beyond the faces of the under-cut teeth 234^a on the main rack bar, as shown in Figs. 20 and 21 and, since the teeth of the rack bar 234 are under-cut, the teeth 233^a do not contact with the teeth 234^a during the subsequent travel of the carriage and bedplates beneath the transfer cylinder with the cylinder in contact with the plates or sheet carried by the bedplate. This eliminates the possibility of any creeping of the impression on the transfer cylinder due to the meshing of the gears when an impression is being taken from the lithographed sheet 80. When the transfer cylinder 44 is first lowered, registration is obtained by the meshing of the teeth 233^a of the gear with the teeth of the auxiliary rack bars 235 and 236 and, at this time, the bearers 230 do not contact with the bearing surfaces 231 by reason of the fact that the portions 230^a of the bearers are ground off in the region between the edges of the rubber blanket 175 so that the initial rotation of the cylinder 44 is effected by the intermeshing teeth of the gear 233 and the composite rack bars 234, 235 and 236 before the bearers 230 pass into engagement with the bearing surfaces 231. After the initial operation of effecting registration of the cylinder 44 with respect to the travel of the bedplate, the rotation of the cylinder is effected entirely by the contacting surfaces of the bearers 230 and the parts 231, but the teeth 233^a of the gear continue to mesh with the teeth of the rack bar 234 in clearance position as heretofore explained. If the carriage 40 is moved longitudinally of the machine when the cylinder 44 is elevated, the teeth 233^a continue to mesh with the teeth 234^a of the rack bar and,

in this case, the teeth will contact with each other so that the longitudinal movement of the carriage will rotate the cylinder and prevent it from getting out of proper position with respect to the travel of the bedplates. 70

The screw shaft 37 by which the longitudinal movement of the carriage 40 is effected is driven by an electric motor 240 which is connected by a belt 241 with a pulley 242 mounted on the end of the shaft 37, as shown in Fig. 6. In order that the screw shaft 37 may come to rest promptly when the motor 240 is stopped, thereby preventing over-running of the carriage 40, the shaft 37 is provided with a friction wheel 242^a surrounded by a friction strap or housing 243 formed in two parts 243^a and 243^b, the latter of which is secured to the frame member 32^b. The part 243^a is provided with lateral projections 244 adapted to overlie similar projections 245 on the part 243^b and 85 bolts extend downwardly from the part 244 through apertures 246 in the part 245 some of these bolts having coiled springs 247 mounted thereon between the lugs 245 and the nuts 248 so that the springs serve to 90 maintain in contact with the surface of the friction wheel 242, the friction plates 249 of leather or the like which are secured on the inside of the part 243^a of the housing. By adjusting the nuts 248, the degree of frictional contact may be regulated in order to arrest the movement of the screw shaft 37 in the manner desired after the motor 240 has been stopped. 95

The motor 240 may be either a direct current motor or an alternating current motor but, for example, there is illustrated in the drawings an alternating current three phase system which is automatically controlled so that the motor may be conveniently started 100 and stopped by the operator and its direction of rotation automatically reversed by control of mechanism which is operated when the carriage 40 reaches either limit of its travel. As shown in Fig. 26, a three phase alternating current motor is supplied with electric current from a suitable source through three line wires 251, 252 and 253. The supply of current from these line wires to the motor 240 is controlled by an electro-magnetic switch 255, a reversing controller 256, two starting switches 257 and 258, and a stopping switch 259. The starting switch 257 is located in a casing 260 on the side frame 31 adjacent the lever 217, as shown in Fig. 1, 110 and the other starting switch 258 is located with the stopping switch 259 in a casing 261 located adjacent the other operating lever 222, the switch casings being connected by a conduit 262 in which the electric conductors 115 are located. One of the line conductors 251 leads through the electro-magnetic switch 255 directly to the motor, as shown in Fig. 26, and the other two line conductors 252 and 253, after passing through the electro-mag- 120

125

130

netic switch 255, are carried to the controller 256 having contacts which are adapted to be operated, as hereinafter described, for reversing the connections of these conductors, at 5 the ends of the path of travel of the carriage 40, so that the direction of rotation of the motor is automatically reversed when the carriage reaches the end of its travel in either direction. The starting switches 257 and 258 10 are normally open and the instantaneous closing of either of them by the fingers of the operator serves to operate the electro-magnetic switch 255 so that the contacts thereof close and start the motor in operation. When it is 15 desired to stop the operation of the motor, the electro-magnetic switch 255 is operated to open the circuit by the manual manipulation of the stopping switch 259.

The controller 256 comprises a casing 265 20 having mounted therein two series of stationary electrical contacts 266 and 267 adapted to be engaged by the movable contacts 268, all of these contacts being connected in the electrical circuit as shown in Fig. 26. The 25 movable contacts 268 are actuated by the shaft 269 which projects through the end wall of the casing 265 and has fixed thereon a disc 270 provided with a pair of notches 271 and 272, as shown in Fig. 24, adapted to 30 be engaged by rollers 273 mounted on the two locking levers 274 and 275. A U-shaped bracket 276 is secured to the base of the controller casing, and the upwardly extending arms of this bracket are connected by coil 35 springs 277 and 278 to the locking levers 274 and 275, respectively. The springs 277 and 278 hold rollers 273 in contact with the peripheral surface of the disc 270 so that when the disc is turned to proper position the roller 273 will engage one or the other of the notches 271 and 272. Each of the locking levers 274 and 275 has a roller 279 pivotally 40 mounted on the upper end thereof to be engaged by a tripping member 280 of angular form, one of which is mounted at each end of the carriage 40, as shown in Figs. 6 and 7. The controller 256 is mounted on a bracket 281 secured to the side frame 31, as shown in 45 Fig. 9, and this bracket is provided with a pair of upwardly extending arms 282 having guideways 283 formed in the upper part thereof to receive a slidably mounted bar 284 having formed therein a plurality of rack teeth 284^a arranged to mesh with the teeth of a segmental gear 285 secured by cap screws 286 on an arm 287 which is fixed to the end of the controller shaft 269, at the end of the controller opposite the disc 270. When the 50 bar 284 is moved longitudinally of the machine in its guideway 283, the resulting angular movement of the segmental gear 285 moves the controller shaft 269 to throw the movable contacts 268 of the controller to one extreme position or the other so that they 55 engage the stationary contacts 266 or the sta-

tionary contacts 267, thereby controlling the direction of rotation of the motor 240. The extent of movement of the segmental gear 285 is determined by the engagement of the arm 287 with the stop members 288 which are secured to the end wall of the controller casing 265, as shown in Fig. 25. The bar 284 by which the controller 256 is operated, is provided at opposite ends with oppositely directed flanges 284^b and 284^c which are 70 adapted to be engaged at either end of the path of travel of the carriage by one or the other of two actuating rods 290 which are slidably mounted in the depending arms 291^a of brackets 291 secured to the under-side of 75 the carriage 40 at each end thereof, as shown in Figs. 6 and 7. The movement of each actuating rod 290 away from the central part of the carriage 40 is limited by a cotter pin 292 passing through the rod, and the rod is 80 normally moved toward the end of the carriage by a coil spring 293 which is mounted thereon, as shown particularly in Fig. 22, between one of the bracket arms 291^a and a collar 294 fixed on the rod. As the carriage 40 85 approaches either end of its path of travel, one of the rollers 279 on the locking lever 274 or 275 which carries the roller 273 then in engagement with one of the notches 271 or 272, is engaged by one of the depending 90 tripping members 280 carried by the carriage, with the result that the roller 273 mounted on the locking levers 274 or 275 in question, is moved out of engagement with the notch in the disc 270 so that the controller shaft 269 is then free to turn. Just after the disc 270 is released, one of the flanges 284^b or 284^c of the operating bar 284 is engaged by one or the other of the actuating rods 290, depending upon the direction of movement of the carriage 40. When this occurs, the engaged rod 290 moves longitudinally in the supporting bracket 291 and the spring 293 mounted on the rod is compressed until the pressure acting on the bar 284 is sufficient to actuate the segmental gear 285 and thereby throw the controller to its other extreme position through the rotation of the shaft 269. When the movable contacts 268 of the controller reach that position which effects the reversal of the direction of rotation of the motor 240, as determined by the engagement of the arm 287 with one or the other of the stops 288 mounted on the end wall of the controller, the roller 273 on the other one of the two operating locking levers 274 or 275, which was in its outer position during the preceding longitudinal movement of the carriage 40, is moved inwardly by its connected spring 277 or 278, thereby causing the roller 273 thereon to engage one of the notches 271 or 272 to hold the controller in the reversed position. The momentary interruption of the circuit during the movement of the movable contacts of the controller from one position 100

105

110

115

120

125

130

to the other serves to stop the motor 240 simultaneously with the reversal of the electrical connections to the motor, so that the motor can subsequently be started in operation 5 to effect further movement of the carriage 40 in the reverse direction only by depressing one or the other of the starting switches 257 or 258. After the circuit of the motor has been interrupted by the initial movement of 10 the controller mechanism, the continued movement of the rack bar 284 to complete the reversal of the electrical connection to the motor 240 is effected by one of the actuating rods 290, the energy stored up in the connected spring 293 being sufficient to continue 15 the movement of the rack bar 284 until the segmental gear 285 reaches the limit of its movement.

Two of the starting switches 257 and 258 20 are provided at convenient points on one side frame 31 so that the machine can be started conveniently from either of the positions adjacent the operating levers by which the transfer cylinder 44 is raised and lowered. 25 One of the starting switches 258 is located adjacent the stopping switch 259 so that these switches may be alternately depressed in succession by the operator for the purpose of effecting an intermittent longitudinal movement 30 of the carriage 40 for positioning purposes. By means of this construction and arrangement of the actuating mechanism for the carriage 40, it will be apparent that at each end of its path of travel, the carriage 40 is 35 automatically stopped and the connections of the motor are reversed so that the next movement of the carriage is in the reverse direction. At one end of the machine, the stopping 40 of the motor and the reversal of its connection by the operation of the controller takes place simultaneously with the automatic elevation of the transfer cylinder 44 out of contact with the paper sheet on the bedplate 42.

45 In the operation of the machine, with the carriage 40 at the right hand end of the machine, as viewed in Fig. 1, the operator places the zinc plate 80 on the bedplate 41 and secures it into position in the manner 50 heretofore described, and one of the starting switches 257 or 258 is then depressed with the result that the carriage 40 is moved by the motor to the other end of the machine, this movement taking place with the transfer cylinder 44 in its elevated position. The zinc plate on the bedplate 41 is preferably 55 inked before the carriage is moved to the left-hand end of the machine, as viewed in Fig. 1, and when the carriage reaches the last-mentioned position, the paper sheet 125 60 is placed in position on the bedplate 42, the edges of the paper sheet being positioned in the manner heretofore described. The cylinder 44 is then lowered by the operation of 65 the lever 222, and the motor having been

automatically stopped by the controller when the carriage reaches the left-hand end of the machine, the operator then starts the motor by again depressing one of the starting switches, with the result that the carriage 70 moves to the right-hand end of the machine, as viewed in Fig. 1, and the impression on the zinc plate is transferred to the cylinder 44 and by that cylinder impressed on the paper sheet 125. When the carriage 40 reaches the 75 right-hand end of the machine again, the cylinder 44 is automatically elevated and the motor 240 is automatically stopped simultaneously with the reversal of the said connection. In addition to the means for automatically elevating the transfer cylinder 44, the lever 217 is provided, as heretofore explained, for effecting a manual elevation of the transfer cylinder 44 at any desired point 80 in the operation of the machine. The provision of two pedals 140 makes it possible to elevate the grippers 126 to permit removal of the paper sheet 125 when the carriage 40 is at either limit of its movement. The motor 240 may of course be stopped at any point in 85 the movement of the carriage by manipulating the switch 259 and, when the circuit of the motor is broken either by the operation of the stopping switch or by the operation of the controller, the friction brake on the screw 90 shaft 37 promptly brings the carriage 40 to rest.

Although but one embodiment of the invention has been shown and described, it will 100 be understood that it may be constructed in various other forms within the scope of the appended claims.

I claim:

1. The combination in a proof press of a bedplate, a carriage supporting said bedplate, a transfer cylinder, means for moving said carriage transversely to the axis of said cylinder, means for raising and lowering said transfer cylinder, means for causing the movement of said carriage to effect rotation of said cylinder, a gear carried by said cylinder, a rack bar carried by said carriage, and means for positioning said cylinder with respect to said carriage to cause said gear to mesh in clearance position with the teeth of 115 said rack bar.

2. The combination in a proof press of a bed plate, a transfer cylinder, a carriage supporting said bed plate and movable transversely to the axis of said cylinder, driving means for said carriage having operating connections, means for effecting rotation of said cylinder by the movement of said carriage, and means actuated automatically 120 when said carriage reaches the end of its path of travel for reversing the operating connections of said driving means.

3. The combination in a proof press of a bed plate, a transfer cylinder, a carriage supporting said bed plate and movable trans- 125

versely to the axis of said cylinder, driving means for said carriage having operating connections, means for effecting rotation of said cylinder by the movement of said carriage, means actuated automatically when said carriage reaches the end of its path of travel for reversing the operating connections of said driving means, and means actuated automatically when said carriage reaches the end of its path of travel for elevating said cylinder.

4. The combination in a proof press, of a carriage, a bedplate supported by said carriage, a transfer cylinder, means for moving said carriage transversely to the axis of said cylinder, means for raising and lowering said cylinder, and gear teeth carried by said carriage and said cylinder to intermesh with each other in any position of said cylinder, 20 some of said teeth being adjustable in position to effect a predetermined registration of said cylinder with respect to said bedplate when said cylinder is lowered and to cause said gear teeth to mesh without contacting with each other in the subsequent movement of said carriage.

5. The combination in an offset proof press, of a carriage, a pair of bedplates supported by said carriage, a transfer cylinder, means for raising and lowering said bedplates, means for raising and lowering said cylinder, means for moving said carriage transversely to the axis of said cylinder, intermeshing teeth carried by said carriage and said cylinder for effecting registration of said cylinder and said bedplates when said cylinder is moved into operative position, 35 said cylinder and said carriage having surfaces adapted to coact after said registration has been effected to cause rotation of said cylinder upon movement of said carriage.

6. The combination in a proof press of a carriage, a bedplate supported by said carriage, a transfer cylinder, means for moving said carriage transversely to the axis of said cylinder, means for moving said cylinder toward and from the path of travel of said carriage, a gear carried by said cylinder, a rack bar carried by said carriage to mesh with said gear, said rack bar comprising a complementary section, and means for adjusting said section to vary the spaces between the rack bar teeth engaged by said gear teeth when said cylinder is moved into operative position with respect to said bedplate.

7. The combination in a proof press of a carriage, a bedplate supported by said carriage, a transfer cylinder, means for moving said carriage transversely to the axis of said cylinder, means for moving said cylinder toward and from the path of travel of said carriage, a gear carried by said cylinder, a rack bar carried by said carriage to mesh with said gear, said rack bar comprising a plurality of complementary sections, and

means for adjusting said sections longitudinally of said rack bar to vary the spaces between the composite rack bar teeth engaged by said gear teeth when said cylinder is moved into operative position with respect to 70 said bedplate.

8. The combination in a proof press of a carriage, a bedplate supported by said carriage, a transfer cylinder, means for moving said carriage transversely to the axis of said cylinder, means for effecting rotation of said cylinder by the movement of said carriage, a gear carried by said cylinder, a rack bar carried by said carriage to mesh with said gear, said rack bar having a slot therein, a plurality of complementary rack bar sections mounted in said slot, and means for adjusting said sections to cause the teeth thereof to overlap the teeth of said first-mentioned rack bar to thereby position the teeth of said gear to mesh in clearance position with the teeth of said rack bar after said gear teeth have passed out of engagement with said complementary rack bar sections.

9. The combination in a proof press of a frame, trackways carried by said frame, rollers mounted on said trackways, a carriage supported on said rollers, a bedplate mounted on said carriage, and means for preventing lateral movement of said carriage in said frame.

10. The combination in a proof press of a frame, trackways carried by said frame, rollers mounted on said trackways, a carriage supported on said rollers, a bedplate mounted on said carriage, additional trackways carried by the sides of said frame, and rollers mounted at the sides of said carriage to coact with said additional trackways to prevent lateral movement of said carriage during its 105 travel on said first-named rollers.

11. The combination in a proof press of a frame, trackways carried by said frame, rollers mounted on said trackways, a carriage supported on said rollers, a bedplate mounted on said carriage, additional trackways carried by the sides of said frame, and rollers mounted at the sides of said carriage to coact with said additional trackways to prevent lateral movement of said carriage during its travel on said first-named rollers, 115 some of said last-named rollers being resiliently mounted on said carriage.

12. The combination in a proof press of a frame, a bedplate carried by said frame, 120 means for moving said bedplate with respect to said frame, a transfer cylinder, eccentrics having parts of said cylinder journaled therein, a shaft for operating said eccentrics, and means actuated by the movement of said bedplate for turning said shaft and thereby moving said cylinder with respect to the path of travel of said bedplate.

13. The combination in a proof press of a frame, a transfer cylinder, trunnions mount- 130

- ed on the ends of said cylinder, eccentrics having said trunnions journaled therein, bearings for said eccentrics carried by said frame, a shaft having connections to operate 5 said eccentrics, a lever for turning said shaft in one direction, and a second lever for turning said shaft in the other direction.
14. The combination in a proof press of a frame, a transfer cylinder, trunnions mounted on the end of said cylinder, eccentrics having said trunnions journaled therein, bearings for said eccentrics carried by said frame, a shaft having connections to operate said eccentrics, a lever for turning said shaft in 10 one direction, a second lever for turning said shaft in the other direction, and adjustable means for limiting the movement of said levers.
15. The combination in a proof press of a frame, a transfer cylinder, means including an eccentric for moving said cylinder transversely to its axis, a pivoted arm, a link connecting said arm to said eccentric, a pin projecting from said arm, and a lever having a 15 notch to receive said pin.
16. The combination in a proof press of a frame, a transfer cylinder, means including an eccentric for moving said cylinder transversely to its axis, a pivoted arm, a link connecting said arm to said eccentric, a pin projecting from said arm, a lever having a notch to receive said pin, and an adjustable stop member adapted to engage said lever on the 20 side thereof opposite said notch.
17. The combination in a proof press of a frame, a transfer cylinder, means including an eccentric for effecting movement of said cylinder transversely to its axis, an eccentric arm connected to said eccentric, a rod pivotally connected to said eccentric arm, a pivoted crank arm connected to said rod, a link pivotally connected to said crank arm and having a slot therein, a lever pivoted on said frame, and a pin projecting from said lever 25 and engaging said slot.
18. The combination in a proof press of a frame, a transfer cylinder, means including an eccentric for effecting movement of said cylinder transversely to its axis, an eccentric arm connected to said eccentric, a rod pivotally connected to said eccentric arm, a pivoted crank arm connected to said rod, a link pivotally connected to said crank arm and having a slot therein, a lever pivoted on said 30 frame, a pin projecting from said lever and engaging said slot, and an adjustable stop member for limiting movement of said lever in one direction.
19. The combination in a proof press of a frame, a transfer cylinder, means including an eccentric for effecting movement of said cylinder transversely to its axis, an eccentric arm connected to said eccentric, a rod pivotally connected to said eccentric arm, a piv- 35 oted crank arm connected to said rod, a link pivotally connected to said crank arm and having a slot therein, a lever pivoted on said frame, and a pin projecting from said lever and engaging said slot, an adjustable stop member for limiting movement of said lever in one direction, a pin projecting from said crank arm, and a second lever pivotally mounted on said frame and having a notch to receive said last-named pin.
20. The combination in a proof press of a frame, a transfer cylinder, means including an eccentric for effecting movement of said cylinder transversely to its axis, an eccentric arm connected to said eccentric, a rod pivotally connected to said eccentric arm, a pivoted crank arm connected to said rod, a link pivotally connected to said crank arm and having a slot therein, a lever pivoted on said frame, a pin projecting from said lever and engaging said slot, an adjustable stop member for limiting movement of said lever in one direction, a pin projecting from said crank arm, a second lever pivotally mounted on said frame and having a notch to receive said last-named pin.
21. The combination in a proof press of a bedplate, a pair of shafts supporting said bedplate, eccentric having said shafts journaled therein, bearings for said eccentrics, arms extending radially from said eccentrics, a rod extending between said arms, means adjustably connecting said rod to said arms to permit adjustment of the relative angular positions of said arms, and means for actuating said rod to rotate said eccentrics.
22. The combination in a proof press of a bedplate, a shaft supporting said bedplate, a frame, adjusting members journaled in said frame and having said shaft journaled eccentrically therein, a sliding frame having connections to said adjusting members to effect rotation thereof, and means for effecting movement of said sliding frame.
23. The combination in a proof press of a bedplate, a shaft supporting said bedplate, a frame, adjusting members journaled in said frame and having said shaft journaled eccentrically therein, a sliding frame having connections to said adjusting members to effect rotation thereof, means for effecting movement of said sliding frame, and graduated means for indicating the extent of said movement.
24. The combination in a proof press of a frame, a carriage movable with respect to said frame, a pair of bedplates, two pairs of shafts for perfectly supporting said bedplates, eccentrics journaled in said carriage and having said shafts journaled therein, and means for independently adjusting the eccentric members for each pair of shafts to effect the

raising and lowering of said bedplates independently of each other.

25. The combination in a proof press of a frame, a carriage movable with respect to said frame, a pair of bedplates, two pairs of shafts for perfectly supporting said bedplates, eccentrics journaled in said carriage and having said shafts journaled therein, means for independently adjusting the eccentric members for each pair of shafts to effect the raising and lowering of said bedplates independently of each other, and means for independently adjusting the angular position of each eccentric member to change the normal positions of different portions of each bedplate.

26. The combination in a proof press of a bedplate, a plurality of grippers adapted to engage a paper sheet on said bedplate, a shaft supporting said grippers, and means permitting a limited angular movement of each of said grippers on said shaft.

27. The combination in a proof press of a bedplate, a plurality of grippers adapted to engage a paper sheet on said bedplate, a shaft supporting said grippers, means permitting a limited angular movement of each of said grippers on said shaft, and resilient means tending normally to move said grippers toward said bedplate.

28. The combination in a proof press of a bedplate, a plurality of grippers adapted to engage a paper sheet on said bedplate, a shaft supporting said grippers, means permitting a limited angular movement of each of said grippers on said shaft, resilient means tending normally to move said grippers toward said bedplate, and means for locking said shaft to move said grippers away from said bedplate.

29. The combination in a proof press of a frame, a carriage movable in said frame, a bedplate carried by said carriage, a shaft journaled in said carriage, a plurality of grippers mounted on said shaft and adapted to engage a paper sheet on said bedplate, means tending normally to hold said grippers in engagement with said sheet, an arm mounted on said shaft, and manually operated means adapted to engage said arm in different positions of said carriage for rocking said shaft to release said paper sheet from said grippers.

30. The combination in a proof press of a bedplate adapted to support a paper sheet, a rock shaft, a plurality of grippers mounted on said shaft to engage said sheet, and a plurality of paper positioning members mounted on said shaft in alternation with said grippers.

31. The combination in a proof press of a bedplate adapted to support a paper sheet, a shaft, a plurality of grippers keyed on said shaft and adapted to engage the upper surface of said paper sheet, a plurality of posi-

tioning devices pivotally mounted on said shaft and adapted to engage the end of said paper sheet, and means for rocking said shaft to move said grippers out of engagement with said paper sheet.

32. The combination in a proof press of a bedplate adapted to support a paper sheet, a shaft, a plurality of grippers keyed on said shaft and adapted to engage the upper surface of said paper sheet, resilient means tending normally to hold said grippers in engagement with said paper sheet, means for rocking said shaft to release said paper sheet, a positioning device pivotally mounted on said shaft and having an adjustable part adapted to engage the end of said paper sheet, and resilient means tending normally to hold said adjustable part in engagement with said bedplate.

33. The combination in a proof press of a bedplate adapted to support a paper sheet, said bedplate having a transverse groove therein, a register bar slidably mounted in said groove, a positioning member carried by said register bar, and means for adjusting said register bar transversely of said bedplate.

34. The combination in a proof press of a bedplate for a paper sheet, said bedplate having a transverse groove in the upper surface thereof, a register bar mounted in said groove, a positioning member, means for mounting said positioning member in any one of a plurality of positions on said register bar, and means for adjusting said register bar in said groove.

35. The combination in a proof press of a bedplate having a groove therein, a register bar slidably mounted in said groove, an adjusting member having a rotative engagement with said bedplate and a threaded connection with said register bar, and resilient means for preventing looseness in the connection between said adjusting member and said register bar.

36. The combination in a proof press of a frame, a carriage having movement in said frame, a bedplate mounted on said carriage, a transfer roll, means comprising a motor for effecting movement of said carriage, means for reversing the direction of rotation of said motor at the end of the path of travel of said carriage, and means for moving said transfer cylinder away from said bedplate at the end of the path of travel of said carriage.

37. The combination in a proof press of a frame, a carriage having movement in said frame, a bedplate mounted on said carriage, a transfer cylinder adapted to cooperate with said bedplate, means comprising a motor for effecting movement of said carriage, means for reversing said motor, means for automatically operating said reversing means of said motor at the end of the path of travel

- of said carriage, and means for automatically moving said transfer cylinder away from said bedplate at the end of the path of travel of said carriage.
5. 38. The combination in a proof press of a bedplate, a plurality of rotatably mounted cams for independently supporting different parts of said bedplate, means for simultaneously rotating all of said cams for effecting a uniform upward adjustment of all parts of said bedplate, and means for independently adjusting the angular positions of said cams. ¹⁰
